(57) **CLAIM**

The ornamental design for a barbell end cap self-mobilization tool, as shown and described.

DESCRIPTION

FIG. 1 is a top plan view of a barbell end cap self-mobilization tool;

FIG. 2 is a front elevational view thereof, the rear, left and right side elevational views being the same image thereof;

FIG. 3 is a bottom view thereof;

FIG. 4 is cross section view taken along the lines 4-4 from FIG. 2 thereof;

FIG. 5 is an isometric view thereof; and,

FIG. 6 is side view of a barbell end cap self-mobilization tool shown in use thereof.

The broken lines are for environmental purposes only and

form no part of the claimed design.

The claimed barbell end cap self-mobilization tool mounts at distal ends of a barbell for massaging and self-mobilization.
